Patented Apr. 12, 1927.

1,624,452

UNITED STATES PATENT OFFICE.

GEORGE W. WHITEHEAD, OF VINCENNES, INDIANA.

WINDMILL.

Application filed June 26, 1924. Serial No. 722,589.

This invention relates to wind-mills and its object is to provide improved and simplified mechanism for regulating the operation of mills of this character and controlling the power delivered thereby. The objects and advantages of the invention will be more fully understood from the following specification, taken in connection with the accompanying drawings forming a part thereof and in which:

Fig. 1 is a side elevation of my improved construction, the tower being partially broken away;

Fig. 2 is an enlarged elevation of a portion of the structure;

Fig. 3 is a plan view partly in section showing the structure illustrated in Figure 2;

Fig. 4 is a cross section substantially on the line 4—4 of Figure 3;

Fig. 5 is a plan view of the mechanism appearing at the top of Figure 1, parts being broken away;

Fig. 6 is a section on the line 6—6 of Figure 3.

Referring to the drawings in detail 10 indicates the tower of the mill which may be of any suitable height and construction. A post or pedestal 11 is rotatably mounted in the tower 10 and preferably supported upon anti-friction bearings (not shown). The pedestal which may be of any desired shape in cross section extends for some distance above the tower and also for some distance down into the tower so that the same is securely braced against lateral movement relative to the tower and the bearings for the same are preferably placed at points A and B respectively at the top of the tower and at the lower end of the post or pedestal. The wind-wheel 12 is mounted on the pedestal 11, this wheel being secured to a horizontal shaft 13 journaled in suitable bearings on the pedestal. A bevel gear 14 is secured to the shaft 13 and meshes with a second bevel gear 15 secured to a vertical shaft which extends downwardly through the pedestal 11 and is rotatably supported therein. This shaft 16 transmits the power from the wind-wheel 12 to any suitable power transmitting mechanism at the bottom of the tower such for example, as the bevel gears 17 and 17^a and shaft 17^b.

A vane 18 is pivotally connected at 18^a to the pedestal 11 opposite the wind-wheel 12. The vane 18 may be locked to the pedestal in a plane parallel to the plane of the wind-wheel 12. To accomplish this, a lever 19 is pivoted at one end to the pedestal 11 and at its opposite end engages a vertical sliding bolt 20 mounted in suitable guide 21 and surrounded by a spring 22 which forces the same upwardly. Secured to the vane 18 is a perforated lug or keeper 23, into the opening of which the bolt 20 is adapted to be forced by the spring 22 when the vane is in a position substantially parallel with the plane of the wheel 12. The bolt 20 may be manipulated from the bottom of the tower by means of a wire or rod 24 which is connected to an intermediate part of the lever 19 and extends downwardly along the pedestal 11 to a convenient point to be grasped by the operator. It will be understood that the rod or wire 24 lies close to the pedestal 11 so that it does not interfere with the rotation of the latter in the tower.

When the bolt 20 is withdrawn from the keeper 23, it will be understood that the vane 18 may move freely relative to the pedestal 11. In other words, the vane 11 is normally free to move about its pivot and will exert an influence on the pedestal and wheel 12 only when it is locked to the pedestal.

For purposes which will later appear it is desirable at times to rotate the pedestal 11 and lock the same in a desired position. To this end, a gear wheel 25 is rigidly secured to the pedestal 11 preferably at the top of the tower 10. A pinion 26 is arranged adjacent the gear wheel 25, this pinion being secured to an operating rod or shaft 27 which extends downwardly through suitable bearings to or near the bottom of the tower and to the lower end of which is secured a hand wheel 28 which serves as means for rotating the rod 27 and the pinion 26. The rod 27 is movable endwise. When in its lowered position the spokes of the wheel 28 are adapted to engage between upstanding lugs 29^a on a block 29 secured to a cross piece of the tower or other suitable support. This serves to hold the rod 27 and pinion 26 against rotation. It will be understood that the lugs 29 are of such height that when the hand wheel 28, shaft 27 and pinion 26 are lifted or moved upwardly, the wheel 28 will be disengaged or freed from the lugs 29 while the pinion 26 is still in mesh with the gear wheel 25. When the parts are thus partially lifted the hand wheel 28 may be rotated to rotate the shaft 27, its pinion 26,

the gear wheel 25, and the pedestal 11. When desired the shaft 27 may be lifted to a point where the pinion 26 will be entirely disengaged from the gear wheel 25. To facilitate raising and lowering of the shaft 27 and the parts connected thereto, I provide a lever, pivotally connected at 31 to a standard 32 mounted on a cross piece of the tower or on any other suitable support. The short end 30^a of this lever is forked, as indicated particularly in Figures 3 and 6, and such forked portion engages over the rod 27 beneath the hub of the hand wheel 28. The long end 30^b of this lever 30 is adapted to engage hooks or keepers 33, 34 secured to a fixed standard 35. It will be apparent that when the long end of the lever 30 is forced downwardly the rod 27 and connected parts will be lifted and vice versa. The parts are so proportioned that when the lever 30 is engaged beneath the hook 33, the hand wheel 28 will be free from the lugs 29^a but the pinion 26 will still be in mesh with the gear wheel 25. But when the lever 30 is moved sufficiently to engage the hook 34, the pinion 26 will be entirely out of mesh with the gear wheel 25. When in its lowered position the lower end of the rod 27 rests in a socket or bearing 36 preferably formed in the block 29.

The operation of the device is briefly as follows: When the pinion 26 is raised so as to be completely out of mesh with the gear wheel 25 and the vane 18 is locked to the pedestal 11, as indicated in Figure 5, the vane will serve to hold the wind-wheel out of the wind. When so arranged all of the parts including the pedestal 11 are free to rotate and the mill is in its inoperative condition. When the pinion 26 is lowered and brought into mesh with the gear wheel 25 by raising the lever 30 and permitting the spokes of the hand wheel 28 to engage the lugs 29^a the pedestal and parts connected therewith will be held against rotation. In other words, the pedestal will be locked in position. When it is desired to rotate the pedestal 11 so as to bring the wind-wheel 12 into or out of the wind, the lever 30 is depressed until it will engage the keeper 33. At such time the hand wheel 28 will be lifted above the lugs 29^a but the pinion 26 will still be in mesh with the gear wheel 25 so that by rotating the hand wheel 28 the pedestal 11 may be turned to any desired position after which the lever 30 may again be raised and the hand wheel 28 permitted to reengage with the lugs 29^a. In case it is desired to completely free the pinion 26 from the gear wheel 25, the lever 30 is depressed to its limit and is engaged with the keeper 34. When it is desired to bring the vane into the position shown in Figure 5 it is only necessary to rotate the pedestal 11 as previously described, until the wind strikes against the side of the vane and the latter will be

forced into the position shown in Figure 5 when the bolt 20 may be manipulated by means of the wire 24 to engage the keeper 33.

It will thus be seen that I have provided an arrangement by which the wind-wheel 12 may be freed from the influence of the vane 18 and the wheel turned into the wind any desired amount so that the amount of power delivered by the wheel may be regulated, assuming that the wind remains in the same direction. When the wind is not too strong the wind-wheel 12 may of course be turned into position to squarely face the wind. In case the wind becomes too strong, the wheel 12 by means of the pinion 26 may be turned more or less out of the wind and locked in any position desired by the wheel 28 and the lugs 29^a. And when it is not desired to use the mill the pinion 26 may be disengaged from the gear wheel 25 and the vane 18 may be locked to the post or pedestal 11 in which position the vane will serve to keep the wind-wheel 12 out of the wind at all times.

Having thus described the invention what is claimed as new and desired to be secured by Letters Patent is:

1. In a windmill, a tower, a pedestal rotatably supported thereon, a horizontal shaft carried by the upper end of said pedestal, a wind wheel secured to said shaft, a vertical shaft arranged in said pedestal, gear mechanism between said shafts, a vane pivotally connected to said pedestal and normally free to move relative to said pedestal horizontally, means for locking said vane to said pedestal in a plane parallel to the plane of said wind-wheel, a gear wheel secured to said pedestal, a pinion for said gear wheel rotatably supported on said tower, means for moving said pinion into or out of mesh with said gear wheel and means for rotating said pinion to cause rotation of said pedestal in the tower.

2. In a wind-mill, a tower, a pedestal rotatably supported therein, a wind-wheel carried by said pedestal, a gear wheel rigidly secured to said pedestal, a pinion rotatably supported on said tower and movable into and out of mesh with said gear wheel, a rod or shaft rigidly secured to said pinion and extending downwardly therefrom, a hand wheel for rotating said shaft and pinion, upwardly extending spaced lugs secured to a tower frame below the hand wheel for locking said hand wheel against rotation, a lever for raising and lowering said shaft and pinion, means for holding said lever in a position where said hand wheel will be free from said lugs while said pinion and gear wheel are still in mesh, and means for holding said hand wheel in a position where said pinion will be entirely out of mesh with said gear wheel and said pedestal free to rotate.

3. In a wind-mill, a tower, a pedestal rotatably supported therein, a wind-wheel carried by said pedestal, a vane pivotally connected to said pedestal and normally free to move relative to said pedestal, a gear wheel rigidly secured to said pedestal, a pinion rotatably supported on said tower and movable into and out of mesh with said gear wheel, a rod or shaft rigidly secured to said pinion and extending downwardly therefrom, a hand wheel for rotating said shaft and pinion, upwardly extending spaced lugs secured to the tower frame below the hand wheel for locking said hand wheel against rotation, a lever for raising and lowering said shaft and pinion, means for holding said lever in a position where said hand wheel will be free from said lugs while said pinion and gear wheel are still in mesh, means for holding said hand wheel in a position where said pinion will be entirely out of mesh with said gear wheel and said pedestal free to rotate, and means for locking said vane to said pedestal in a plane parallel with the plane of said wind-wheel.

4. In a wind-mill, a tower, a pedestal rotatably supported in the upper portion there-

of, a wind-wheel carried by said pedestal, a gear wheel rigidly secured to said pedestal adjacent the top of said tower, a pinion rotatably supported on said tower and movable into and out of mesh with said gear wheel, a rod or shaft secured to said pinion and extending downwardly to a point adjacent the bottom of said tower, a hand wheel for rotating said rod, lugs or projections for engaging and preventing rotation of said hand wheel when said rod is in its lowermost position, said lugs being of such height that said hand wheel may be moved upwardly out of engagement therewith while said pinion is still in engagement with said gear wheel, whereby said gear wheel and pedestal may be rotated to any desired position, a lever for raising and lowering said rod, and means for holding said lever in a position where said hand wheel will be free from said lugs and said pinion partially in mesh with said gear wheel or in a position where said pinion will be entirely free from said gear wheel.

In testimony whereof I hereunto affix my signature.

GEORGE W. WHITEHEAD.
